(57) **CLAIM**

The ornamental design for an item carrier, as shown and described.

DESCRIPTION

FIG. 1 is a front, top, right side isometric view of an item carrier in a first configuration showing the design;

FIG. 2 is a bottom, back, left side isometric view thereof;

FIG. 3 is a front elevational view thereof;

FIG. 4 is a back elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front, top, right side isometric view of the item carrier in a second configuration showing the design;

FIG. 10 is a bottom, back, left side isometric view thereof;

FIG. 11 is a front elevational view thereof;

FIG. 12 is a back elevational view thereof;

FIG. 13 is a left side elevational view thereof;

FIG. 14 is a right side elevational view thereof;

FIG. 15 is a top plan view thereof; and,

FIG. 16 is a bottom plan view thereof.

The item carrier transitions between the configuration shown in FIGS. 1–8 and the configuration shown in FIGS. 9–16.

1 Claim, 12 Drawing Sheets
